DISTILLATION OF HYDROCARBON OILS

Filed July 14, 1928

UNITED STATES PATENT OFFICE

THOMAS S. COOKE, OF NEW YORK, N. Y., AND OSWALD C. BREWSTER, OF CASPER, WYOMING, ASSIGNORS TO STANDARD OIL COMPANY, OF WHITING, INDIANA, A CORPORATION OF INDIANA

DISTILLATION OF HYDROCARBON OILS

Application filed July 14, 1928. Serial No. 292,661.

This invention relates to the distillation of hydrocarbon oils and will be readily understood from the following description taken in conjunction with the accompanying drawing, which shows diagrammatically an apparatus suitable for effecting such distillation.

Referring to the drawing:—

A pipe still 10 is provided, which is adapted to be supplied with oil by the pipe 11. The outlet 12 from the pipe still 10 leads into a suitable separating chamber 13. From the lower end of the chamber 13 a pipe 14, provided with a suitable pump 14^a, leads to a tar heat exchanger 15. In the drawing the tar heat exchanger 15 is represented diagrammatically as a container containing a coil 15^a into which the pipe 14 leads. It must be understood that any form of exchanger providing for indirect heat exchanging contact of tar and oil may be used. The tar outlet 16 from the tar heat exchanger 15 communicates with a valved pipe 17 and with a tar cooler 18 so that the tar can be supplied either relatively cold or relatively warm to storage. A pipe 19 connects the pipes 14 and 16 and suitable valves are provided whereby the tar heat exchanger 15 may be bypassed, the tar passing by pipes 14, 19 and 16 direct from the separating chamber 13 to the tar cooler 18.

From the upper portion of the separating chamber 13 a pipe 20 leads into the lower portion of a fractionating tower 21, which is provided with suitable fractionating devices, for example, bubble-cap plates 22 and bubble caps 23. From the lower end of the tower 21 a pipe 24 leads into pipe 11. The pipe 24 is provided with a suitable pump 25.

A pump 26 is provided for supplying oil to be distilled. The outlet 27 of the pump 26 leads into the tar heat exchanger 15. From the upper side of the tar heat exchanger 15 a pipe 28 leads to an intermediate portion of the tower 21 for the purpose of introducing thereto any vapors formed in the tar heat exchanger 15. The preheated incoming oil emerges from the tar heat exchanger 15 and passes by a pipe 29 to an intermediate point of the fractionating tower

21. A pipe 30 connects the pipes 27 and 29 and suitable valves are provided so that the incoming oil may be by-passed with respect to the tar heat exchanger 15, when desired.

The pipe 27 is connected by a pipe 31 to the inlet 11 of the pipe still 10, and suitable valves are provided whereby a desired portion of the incoming oil may be supplied directly to the pipe still. The pipe 14 is connected to the pipe 31 by the pipe 32 and suitable valves are provided for the purpose of permitting the return of a desired amount of the tar from the separating chamber 13 to the pipe still 10.

From the top of the tower 21 a vapor conduit 33 leads into a suitable condenser 34. The condensate flows out of said condenser by pipe 35. The pipe 36, provided with a pump 37, leads from the pipe 35 into the upper end of the fractionating tower 21 for the purpose of supplying reflux thereto.

If desired, valved conduits 38 may be connected to plates in the upper portion of the tower 21 for the purpose of withdrawing a desired quantity of reflux or distillate therefrom. Such distillate passes by pipe 39 into the upper part of a small bubble cap tower 40. The bubble cap tower 40 is provided at its upper end with the vapor conduit 41 which leads into the fractionating tower 21 at a suitable point which is preferably below the plates to which the pipes 38 are connected. The tower 40 is provided at its base with a pipe 42 for supplying open steam thereinto, and with a liquid outlet 43 which suitably leads to an oil cooler 44, which is suitably cooled by water in known manner. The oil emerges from the oil cooler 44 by the pipe 45. The pipes 17, 35 and 45 are provided with suitable valves 46 whereby the apparatus may be maintained under a desired pressure, which, as will be hereinafter indicated, has important advantages in distillation according to this method.

Suitable float control means (not shown) may be provided in the lower portion of towers 21 and 40 and of separating chamber 13 for the purpose of preventing withdrawal of vapors by the pipes 24, 43 and 14, respectively.

The operation is as follows: Crude oil containing about one per cent water, about fifteen per cent of gasoline, and about four to five per cent of suitable kerosene fractions is supplied by the pump 26 through pipe 27 to the tar heat exchanger 15. In passing through the tar heat exchanger 15 the incoming oil is heated to approximately 425° F. by the hot tar which passes through the 10 coil 15^a. The steam and gasoline vapors which are produced owing to this rise of temperature collect in the upper portion of the heat exchanger 15 and pass by the pipe 28 into an intermediate point of the fractionating tower 21. The preheated liquid oil is conducted by the pipe 29 to an intermediate portion of the tower 21. Said oil descends through the lower plates of the tower 21 countercurrent to the highly heated vapors which are supplied by pipe 20 to a lower point of the tower 21, as will be hereinafter further described. The descending oil is deprived of the lighter fractions by the stripping action of the ascending hot vapors, which are cooled and deprived of certain heavy fractions which are condensed and become part of the descending oil. The temperature of the oil at the bottom of the tower 21 has been increased somewhat, for example, to 460° F. to 475° F. 25 This hot oil is supplied by pump 25 through pipes 24 and 11 to the pipe still 10. As indicated above, a certain quantity of incoming crude oil and/or tar may, if desired, be also supplied to the pipe still 10 by the pipes 31 and/or 32, respectively.

In passing through the pipe still 10 the oil is heated to approximately 575° F. and is conducted to the separating chamber 13 by the pipe 12. The vapors formed by the heating in the pipe still separate from the unvaporized liquid in the separating chamber 13 and the vapors pass by pipe 20 into the lower portion of the column 21 in the manner above described. The tar is pumped by pump 14^a 40 through the pipe 14 through the coil 15^a of the heat exchanger 15 and its temperature is thereby reduced to about 175° F. As indicated above, the heat of the tar is communicated to the incoming crude oil in passing 45 through the tar heat exchanger 15. The tar is then passed by pipes 16 and 17 direct to storage or it may be cooled in the tar cooler 18 by water in well known manner.

The vapors which are admitted into the 55 tower 21 by the pipe 28 together with the vapors admitted into the tower by the pipe 20 and the vapors which have been stripped from the oil descending through the lower part of the tower 21 pass through the plates 60 in the upper portion of said tower countercurrent to reflux supplied by pipe 36.

The upper end of the tower 21 may suitably be maintained at a temperature of about 275° F. by regulating the speed of the reflux 65 pump 37. The distillate is condensed in the

water condenser 34 in the usual manner. The valves 46 are so adjusted as to maintain the apparatus including the condenser 34 under substantial pressure, for example, one atmosphere gage. In this way the cooling efficiency of the condenser water is greatly enhanced. For example, relatively warm condenser water, such as water at a temperature of 85° F. is as effective in condensing effect and gasoline recovery when operating at a pressure of one atmosphere gage, as is water around 50 to 60° F. when operating at atmospheric pressure. Steam in substantial quantity tends to nullify the effect obtained by condensing under superatmospheric pressure. Accordingly it is preferred to avoid as far as possible the introduction of steam or water into the system. It is thus apparent that the present operation is particularly adapted for use under tropical or semi-tropical conditions or where only limited quantities of cooling water are available.

If desired, the kerosene fractions which the crude oil may contain may be readily separated in the following manner: A suitable amount of reflux is drawn off from one or more of the higher plates of the column 21 by the pipes 38 and 39 and supplied to the upper end of the small tower 40. Such oil descends through said tower and collects in the bottom thereof. Open steam is supplied by the pipe 42 in an appropriate amount to strip the oil of sufficient gasoline fractions to yield a satisfactory kerosene. The steam and light fractions pass by pipe 41 into the tower 21 while the kerosene passes by pipe 43 to the cooler 44 and thence to storage by pipe 45.

It will be noted that during the whole process the oil is not subjected to cracking temperatures. This feature of the process ensures products of remarkable stability and purity so that the necessity of acid treatment of the product is avoided in the case of very many crudes, where it would be necessary if cracking temperatures were attained.

Although the present invention has been described in connection with the details of a specific example thereof, it must be understood that it is not intended that such details should be limitative of the scope of the invention except in so far as included in the accompanying claims.

We claim:

1. The method of distilling hydrocarbon oils which consists in preheating said oil by indirect contact with highly heated residue thereby vaporizing a part thereof, supplying said vapors to an intermediate point of a fractionating column, supplying unvaporized oil to an intermediate point of said tower and causing same to flow downwardly through the lower part thereof, passing said oil from the lower part of the tower in a confined stream through a heating zone thereby vaporizing a part thereof, separating

- the vapors therefrom and passing same upwardly through said column countercurrent to said descending oil thereby stripping volatile fractions therefrom, subjecting the combined vapors to fractionation, cooling the combined vapors to condense heavier portions thereof, subjecting the condensed portions to a stripping operation, returning the stripped vapors to said fractionating column and condensing the fractionated vapors. 5
2. The method of distilling hydrocarbon oils which consists in preheating said oil by indirect contact with highly heated residue thereby vaporizing a part thereof, supplying said vapors to an intermediate point of a fractionating tower, supplying unvaporized oil to an intermediate point of said tower and causing same to flow downwardly through the lower part thereof, passing said oil in a confined stream through a heating zone thereby vaporizing a part thereof, separating the vapors therefrom and passing same upwardly through said column countercurrent to said descending oil thereby stripping volatile fractions therefrom, fractionating the combined vapors in the upper portion of said fractionating tower, cooling the vapors to condense a portion thereof, withdrawing said condensed portion and subjecting it to a stripping operation, returning the stripped vapors to said fractionating tower, condensing the fractionated vapors and supplying in the top of said tower condensed fractionated vapors to act as reflux therein. 10 15 20 25 30 35
3. The method of distilling hydrocarbon mineral oils which consists in preheating said oil by indirect contact with highly heated residue thereby vaporizing a part thereof, separately withdrawing the vapors from said preheating operation and supplying said vapors to an intermediate point of a fractionating tower, separately withdrawing unvaporized oil from said preheating operation and supplying said unvaporized oil to an intermediate point of said tower and causing same to flow downwardly through the tower part thereof, passing said oil from said column in a confined stream through a heating zone thereby vaporizing a part thereof without the addition of steam, separating the vapors therefrom and passing same upwardly through said column countercurrent to said descending oil thereby stripping volatile fractions therefrom, fractionating the combined vapors in the upper portion of said fractionating tower, condensing the fractionated vapors under superatmospheric pressure and supplying in the top of said tower condensed fractionated vapors to act as reflux therein. 40 45 50 55 60 65
4. The method of distilling crude petroleum which consists in supplying said crude petroleum to an intermediate part of the fractionating tower, causing liquid portions thereof to descend the lower portion of said tower, thereafter heating said liquid portions in a confined stream to vaporize gasoline and kerosene fractions therefrom, passing said vapors upwardly through said tower countercurrent to said liquid portions, fractionating the vapors in the upper portion of said tower under conditions to provide gasoline vapors at the top of said tower, supplying cooling medium at the top of said tower to act as reflux therein, withdrawing reflux from an elevated part of said tower, stripping said reflux with steam to yield refined kerosene and conveying the stripped vapors and steam to said fractionating tower. 70 75 80 85 90 95 100 105 110 115 120 125
5. The method of distilling hydrocarbon mineral oils under superatmospheric pressure which consists in preheating said oil to about 425° F. by indirect contact with highly heated residue thereby vaporizing a part of said oil, separately withdrawing the vapors from said preheating operation and supplying said unvaporized oil to an intermediate point of a fractionating tower, separately withdrawing unvaporized oil from said preheating operation and supplying said unvaporized oil to an intermediate point of said tower below the point of introduction of said vapors and causing same to flow downwardly through the lower part thereof, passing said unvaporized oil from said column in a confined stream through a heating zone thereby heating it to a temperature of about 575° F. without the addition of steam, separating vapors from said oil and passing same upwardly through said tower countercurrent to said descending oil thereby stripping volatile fractions therefrom, subjecting the combined vapors to fractionation and condensing the fractionated vapors. 125
6. The method of distilling hydrocarbon mineral oils which consists in preheating said oil to about 425° F. by indirect contact with highly heated residue thereby vaporizing a part of said oil, separately withdrawing the vapors from said preheating operation and supplying said vapors to an intermediate point of a fractionating tower, separately withdrawing unvaporized oil from said preheating operation and supplying said unvaporized oil to an intermediate point of said tower below the point of introduction of said vapors and causing same to flow downwardly through the lower part thereof, passing said unvaporized oil from said column in a confined stream through a heating zone thereby heating it to a temperature of about 575° F. without the addition of steam, separating vapors from said oil and passing same upwardly through said tower countercurrent to said descending oil thereby stripping volatile fractions therefrom, subjecting the combined vapors to fractionation and condensing the fractionated vapors under superatmospheric pressure. 130

7. The method of distilling hydrocarbon mineral oils which consists in preheating said oil to about 425° F. by indirect contact with highly heated residue, stripping the unvaporized oil with highly heated vapors, heating the stripped oil in a confined stream to about 575° F. without the addition of steam, separating the vapors thus produced from the residue, passing said residue to the said preheating operation, and passing said separated vapors to the stripping operation, fractionating the vapors from the preheated oil and the stripping operation together, with drawing from said fractionating operation a portion of the resulting condensate and subjecting it to a separate stripping operation, returning the stripped vapors to said fractionating operation, and condensing them under superatmospheric pressure.
8. The method of distilling hydrocarbon oils which consists in supplying oil to be distilled to an intermediate point of a fractionating tower, withdrawing oil from a low point of said tower and supplying same to a pipe still, heating said oil to about 575° F. therein thereby vaporizing part of the oil, separating vapors from said oil and passing them into said tower at a low point thereof, supplying cooling medium to the upper end of said tower to maintain a temperature of about 275° F. therein, withdrawing vapors from the top of said tower and condensing same under superatmospheric pressure, withdrawing liquid from the upper part of said tower and stripping same to produce kerosene and returning the stripped vapors to the tower.
9. The method of distilling hydrocarbon oil which consists in preheating said oil to a temperature of about 425° F. by indirect contact with highly heated residue thereby vaporizing part of the oil, supplying said vapors and the unvaporized oil to an intermediate part of a fractionating tower, withdrawing unvaporized oil from a low point of said tower and passing same through a pipe still, heating said oil to about 575° F. therein and vaporizing part of the oil, separating the vapors thus produced from the residue, supplying said residue to the preheating operation and supplying said vapors to a low point of said tower, supplying cooling medium to the upper end of said tower to maintain a temperature of about 275° F. therein, withdrawing vapors from the top of said tower and condensing same, withdrawing liquid from the upper part of said tower and stripping same to produce kerosene and returning the stripped vapors to the tower.
10. An apparatus for distilling hydrocarbon oils which comprises a preheater, a conduit for supplying oil to be distilled thereto, a fractionating tower, a vapor pipe leading from said preheater to said tower, a conduit for supplying unvaporized oil from said pre-

heater to said tower, a pipe still, means for conveying oil from the base of said tower into said pipe still, a separating chamber into which said pipe still feeds, a conduit for conveying vapors from said chamber to the base of the fractionating tower and a conduit for conveying residue from said chamber to the preheater.

11. An apparatus for distilling hydrocarbon oils which comprises a fractionating tower, a pipe still, a preheater for incoming oil, a conduit for leading oil from said preheater to an elevated point of said tower, a conduit for conducting vapors from said preheater to said tower, a conduit for conducting oil from a low point of said tower into said pipe still, a separating chamber connected to the outlet of said pipe still, a conduit for conducting vapors from said separating chamber into a low point of said tower and a conduit for conducting residue from said chamber to said preheater.

12. An apparatus for distilling hydrocarbon oils comprising a fractionating tower, a pipe still, a separating chamber connected to said pipe still, a conduit for supplying oil to be distilled to an intermediate point of the tower, a conduit for conveying oil from the base of said tower to the pipe still, a vapor conduit extending from said separating chamber to the base of said tower, a second tower, conduits for withdrawing liquid from the upper part of the first tower and supplying it into the upper part of the second tower, a conduit for supplying stripping steam into the base of the second tower, a liquid outlet from the base of the second tower, and a vapor conduit leading from the top of the second tower into the upper part of the first tower.

13. The method of distilling hydrocarbon oils which comprises passing said oil downwardly through a fractionating column, withdrawing said oil from said column and passing it through a heating zone in a confined stream, heating the oil therein to vaporize a part thereof, passing the vapors to said column and causing them to ascend said column countercurrent to said oil whereby the lighter fractions of said oil are vaporized, subjecting the combined vapors to a fractionation operation, withdrawing resulting condensate from said fractionating operation and subjecting it to a stripping operation, returning the resulting stripped vapors to said fractionation operation, and passing the fractionated vapors from said fractionation operation to a condensing operation.

14. The method of distilling hydrocarbon oils which comprises passing said oil downwardly through a fractionating column, withdrawing said oil from said column and passing it through a heating zone in a confined stream, heating the oil therein to vaporize a part thereof, passing the vapors to

said column and causing them to ascend said column countercurrent to said oil whereby the lighter fractions of said oil are vaporized, subjecting the combined vapors to a fractionation operation, withdrawing resulting condensate from said fractionating operation and subjecting it to a stripping operation, returning the resulting stripped vapors to said fractionation operation, withdrawing the stripped condensate from the system, and passing the fractionated vapors from said fractionation operation to a condensing operation.

In testimony whereof we have hereunto set our hands and seals at New York, N. Y., the 18th day of June, 1928, and at Casper, Wyoming, the 7th day of July, 1928, respectively.
